US00D993183S

(12) **United States Design Patent** (10) **Patent No.:** **US D993,183 S**
(45) **Date of Patent:** **** Jul. 25, 2023**

(54) **CONNECTOR SHELL**

(71) Applicant: **LUXSHARE PRECISION INDUSTRY CO., LTD.**, Shenzhen (CN)

(72) Inventors: **Yingbin Pu**, Shenzhen (CN); **Lei He**, Shenzhen (CN)

(73) Assignee: **LUXSHARE PRECISION INDUSTRY CO., LTD.**, Shenzhen (CN)

(**) Term: **15 Years**

(21) Appl. No.: **29/805,541**

(22) Filed: **Aug. 27, 2021**

(30) **Foreign Application Priority Data**

Jun. 18, 2021 (CN) 202130379424.4

(57) **CLAIM**

The ornamental design for a connector shell, as shown and described.

DESCRIPTION

FIG. 1 is a perspective view of a connector shell showing my new design;

FIG. 2 is a front elevation view thereof;

FIG. 3 is a rear elevation view thereof;

FIG. 4 is an enlarged left elevation view thereof;

FIG. 5 is an enlarged right elevation view thereof;

FIG. 6 is a top plan view thereof; and,

FIG. 7 is a bottom plan view thereof.

1 Claim, 7 Drawing Sheets
